VOICE REFLECTOR

Carolyn H. MacFarlane, 2926 Avalon Ave.,
Berkeley, Calif.

Filed Nov. 2, 1964, Ser. No. 82,418

Term of patent 14 years

(Cl. D25—1)

FIGURE 1 is a side elevational view of a voice reflector showing my new design.

FIGURE 2 is a front elevational view of the voice reflector looking along the line 2—2 of FIGURE 1.

FIGURE 3 is a top plan view of the voice reflector looking along the line 3—3 of FIGURE 2.

FIGURE 4 is a rear elevational view of the voice reflector looking along the line 4—4 of FIGURE 1.

FIGURE 5 is a reduced side elevational view of the voice reflector with the broken lines showing a person's head for purposes of illustration only.

I claim:

The ornamental design for a voice reflector, substantially as shown and described.
